ABSTRACT OF THE DISCLOSURE

A transparent liquid detergent composition, excellent in bleaching and cleaning properties, consisting essentially of a surface active agent represented by a general formula,

(wherein R stands for an alkyl group having 8 to 22 carbon atoms, n is an integer of 1 to 40, m is an integer of 1 or 2 and M is an alkali metal), an alkali metal hypochlorite and an alkali agent dissolved in water, said alkali metal hypochlorite containing less than $\frac{1}{10}$ mol of alkali metal chloride per mol of the hypochlorite and the available chlorine content of the composition being 0.5–13% by weight.

This invention relates to a cleaning and bleaching liquid composition containing hypochlorite.

More particularly, it relates to a cleaning and bleaching liquid composition, characterized by consisting of a surface active agent represented by a general formula (1)

(wherein R stands for an alkyl group having 8 to 22 carbon atoms, n is an integer of 1 to 40, M is an integer of 1 or 2 and m is an alkali metal), an alkali metal hypochlorite and an alkali agent as indispensable components, dissolved in water, said alkali metal hypochlorite containing less than $\frac{1}{10}$ mol of an alkali metal chloride per mol of the hypochlorite and the available chlorine content of the composition being 0.5–13% by weight.

There have been presented various surface active agents that are dissolved stably in sodium hypochlorite solution; for example, there are sodium alkylidiphenyloxide sulfonate (Japanese patent publication No. 6,268/1963 and USP No. 3,172,861), a compound represented by a general formula,

(wherein R is an alkyl group having 8 to 9 carbon atoms, Me is an alkali metal, and n is an integer of 10 to 40) (Japanese patent publication No. 2,103/1968), and a compound represented by a general formula,

(wherein R and R' are alkyl groups whose carbon atoms sum up to 17, X is a member of the group consisting of $-\text{COOMe}$, $-\text{SO}_3\text{Me}$, $-\text{OSO}_3\text{Me}$, or

2

Y is a member of the group consisting of $-\text{COOMe}$ or $-\text{OSO}_3\text{Me}$, and Me is an alkali metal) (Japanese patent publication No. 7,976/1970).

These compounds are, however, not satisfactory in all the required properties such as solution stability, cleaning property, wetting power, foaming power and softening property.

We have found that the surface active agent represented by the above-described Formula 1 is a compound that can satisfy all of these required properties.

10 A conventional commercially-available bleaching liquid employs a hypochlorite containing an equimolar amount of an alkali metal chloride, as it is the most economical; however, the alkali metal hypochlorite used in the composition of this invention (usually the sodium or potassium salt) contains either no alkali metal chloride or less than $\frac{1}{10}$ mol per mol of the alkali metal chloride of the hypochlorite.

15 The stability of a hypochlorite solution depends on the strength of the ions contained in it, but in the system containing a surface active agent represented by the Formula 1, the decomposition of the surface active agent due to sodium hypochlorite and the decomposition of sodium hypochlorite has been found to be much more influenced by the presence of sodium chloride, than by sodium sulfate or sodium orthophosphate, even with the same strength of ions.

20 In the present invention, accordingly, it is important for the stability of the composition to remove alkali metal chlorides which will particularly accelerate the decomposition of the surface active agent by hypochlorite, in addition to lowering the strength of ions of inorganic salts.

25 The amount of the surface active agent of the Formula 1 used in the composition of this invention is about 0.5 to 20% by weight of the composition.

30 The amount of the hypochlorite used is selected so as to make the available chlorine content in the composition to be about 0.5 to 13% by weight. When the content is less than 0.5%, the bleaching effect is unsatisfactory and when it is more than 13%, the composition tends to be unstable.

35 As the alkali agent, alkali metal hydroxides are the most preferable, but carbonates, orthophosphates or metasilicates may be used. When the composition is to be stored particularly for a long time, alkali metal hydroxides such as sodium hydroxide and potassium hydroxide are preferable.

40 These alkali agents are effective for the stabilization of the surface active agent and act as a buffer for the system. The amount of the alkali agent to be used in the composition of this invention is 0.5 to 2.0% by weight, preferably 0.8 to 1.3% by weight of the composition.

45 The composition of this invention is a transparent liquid detergent that undergoes neither the decomposition of the hypochlorite and the surface active agent nor any turbid precipitation even after storing it for a long time, and it is excellent in its bleaching and cleaning properties.

50 The invention will be explained by several illustrative examples wherein percent are all by weight.

EXAMPLE 1

Percent

65	Sodium hypochlorite	6.30
	Surface active agent (as shown below)	3.00
	NaOH	1.00
	NaCl	0.25

55 Bleaching and cleaning liquor compositions A, B, C, D and E having 6.0% of the available chlorine concentration were prepared according to the above-described composi-

tion with different surface active agents, which are shown below:

Composition	Surface active agent
A	
B	
C	
D	
E	

The stability and the foaming power were determined for each composition, and the results are shown in Table 1.

TABLE 1

	A	B	C	D	E
Stability of the surface active agent, ¹ percent	[Initial stage] 3.00 [After treatment] 2.98 2.79 2.76 2.96 2.95				
Stability of the available chlorine, ¹ percent	[Initial stage] 6.00 6.00 6.00 6.00 6.00 [After treatment] 3.50 3.23 3.18 3.46 3.48				
Foaming power ²	[Decomposition rate] 41.6 46.3 47.0 42.3 42.0 [Initial stage] 0 135 140 136 133				
Softening property ³	4.2 3.2 4.0 1.6 2.0				

¹ 100 grams of a sample were put in a 200 cc. Erlenmeyer flask provided with an air condenser, and heated at 90° C. for 5 hours to accelerate decomposition.

² Ross-Miles foaming test (with 0.2% concentration at room temperature, 23° C.; the values listed are the average of two tests).

³ Commercially available bleached cloth was dipped in a 10% solution at 25° C. for 30 minutes, washed in a water stream and dried with air. The treatment was repeated 10 times to prepare samples. The relative softness of the samples were ranked by a panel of 10 persons who assigned to the samples the rankings of 1 to 5 in the order of decreasing softness. The average of the rankings average by the test panel are listed. The smaller the figure is, the softer is the sample.

The test results show that the compositions D and E, according to the invention, are excellent as a whole.

EXAMPLE 2

The compositions shown in Table 2 were prepared with a sodium hypochlorite solution (available chlorine, 12.5%; sodium chloride, 0.8%).

TABLE 2

	Composition, percent					
	F	G	H	I	J	K
Sodium hypochlorite (as available chlorine)	6.0	5.5	6.5	6.0	6.0	4.0
	2.0			3.0		
		3.0			4.0	
			4.0			1.0
				4.0	1.0	
NaOH	1.0	1.0	1.0	0.0	1.0	1.0
Water						

Each composition was stored at -5° C. for 30 days but it was still transparent and did not show any turbid precipitation. The available chlorine concentrations after storing at 30° C. for 20 days are as follows:

	Percent
F	5.60
G	5.08
H	6.12
I	5.56
J	5.58
K	3.70

A composition prepared with a sodium hypochlorite solution (the available chlorine, 12.3%; sodium chloride, 11.16%) containing sodium chloride in an amount almost similar as the amount of sodium hypochlorite, separated into two layers, when it was used in compositions similar to those of compositions F to K.

EXAMPLE 3

The following compositions were prepared with a sodium hypochlorite solution with a low sodium chloride content (available chlorine, 12.50%; sodium chloride, 0.80%) and a sodium hypochlorite solution with a high sodium chloride content (available chlorine content, 12.34%; sodium chloride, 10.2%).

TABLE 3

Composition, percent	L	M	N
Sodium hypochlorite (as the available chlorine)	6.0	6.0	6.0
	4.0	4.0	
NaOH		1	1
NaCl	0.4	5.0	5.0
Water		Balance	

The composition L remained stable and transparent after storing at room temperature and at -5° C. for 3 months, but the composition M had a high viscosity just after blending and separated into two layers after leaving at room temperature. The composition L had 5.13% available chlorine content after storing at room temperature for 6 months in a closed container, and could be used as a detergent for diapers. The composition N was a composition similar to a conventional commercially-available bleaching liquor, and had 5.20% available chlorine content after storing at room temperature for 6 months.

The wetting power of the 1% solution was 45 seconds with the composition L according to the felt sedimentation test, but the composition N did not sink after 300 seconds.

What we claim is:

1. A cleaning and bleaching liquid composition consisting essentially of an aqueous solution of (A) from about 0.5 to about 20%, by weight of the composition, of surface active agent of the formula

wherein

R is alkyl having 8 to 22 carbon atoms,
n is an integer of 1 to 40,

m is an integer of 1 or 2, and

M is an alkali metal,

(B) an alkali metal hypochlorite selected from the group consisting of sodium hypochlorite and potassium hypochlorite, said alkali metal hypochlorite containing less than $\frac{1}{10}$ mol of alkali metal chloride per mol of the hypochlorite and the available chlo-

rine content of the composition being from 0.5 to 13.0% by weight, and

(C) from about 0.5 to 2.0%, by weight of the composition, of alkali agent selected from the group consisting of hydroxides, carbonates, orthophosphates and metasilicates of sodium or potassium.

2. A cleaning and bleaching liquid composition as claimed in claim 1, in which the amount of said alkali agent is from 0.8 to 1.3% by weight of the composition.

3. The cleaning and bleaching liquid composition as claimed in claim 1, in which said alkali agent is sodium or potassium hydroxide.
